Primary Examiner — Cary M Robinson*Assistant Examiner* — Emily Anna Saunders(74) *Attorney, Agent, or Firm* — Jeenam Park(57) **CLAIM**

The ornamental design for a toy tool box, as shown and described.

DESCRIPTION

FIG. 1 is a front, left and bottom perspective view of a toy tool box, showing my new design;

FIG. 2 is a front, left and bottom perspective view thereof, in an alternate position;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The pattern shown on the surfaces of the toy tool box illustrates a wood grain appearance that is continuous throughout the surfaces on which it is shown.

The shaded portions of the design are included to illustrate the color black.
